(57) **CLAIM**

The ornamental design for the angle recorder for surgery, as shown and described.

DESCRIPTION

FIG. 1 is a front view of the angle recorder for surgery showing our new design;

FIG. 2 is a back elevational view of the angle recorder for surgery;

FIG. 3 is a left elevational view of the angle recorder for surgery;

FIG. 4 is a right elevational view of the angle recorder for surgery;

FIG. 5 is a top plan view of the angle recorder for surgery;

FIG. 6 is a bottom plan view of the angle recorder for surgery; and,

FIG. 7 is a perspective view of the angle recorder for surgery.

1 Claim, 7 Drawing Sheets
